BABY CARRIAGE OR SIMILAR ARTICLE

Louis Gottfried, New York, N. Y.

Application October 25, 1949, Serial No. 5,690

Term of patent 14 years

(Cl. D14—14)

To all whom it may concern:

Be it known that I, Louis Gottfried, a citizen of the United States, residing at New York, in the county of the Bronx and State of New York, have invented a new, original, and ornamental Design for a Baby Carriage or Similar Article, of which the following is a specification, reference being had to the accompanying drawing, forming part thereof.

In the drawing:

Fig. 1 is a front perspective view of a baby carriage or similar article showing my new design; with the carriage, the bumper support and the bumper in upright position;

Fig. 2 is a front perspective view of my design shown in Fig. 1 with the carriage and the bumper support in upright position and the bumper in turned down position, and

Fig. 3 is a front perspective view of my design shown in Fig. 1 with the carriage body in collapsed position, the bumper support in lowered position and the bumper in upright position.

The essential features of my design reside in the portions shown in full lines in the drawing.

I claim:

The ornamental design for a baby carriage or similar article, as shown and described.

LOUIS GOTTFRIED.
